UNITED STATES PATENT OFFICE.

DAVID BOOTH, OF BALTIMORE, MARYLAND.

BOLT.

Application filed May 27, 1926. Serial No. 112,090.

This invention appertains broadly to new and useful improvements in latching devices and has more specific reference to a novel and simplified bolt for securing the doors of garages and like structures in closed position.

An important object of the present invention is to provide such an improved bolt of the character stated having associated therewith 10 with yieldable means for normally urging the same into latching position.

Another object of the present invention is to provide such a bolt of the character stated having incorporated therewith means 15 for retaining the same in its latching position independently of the yieldable means whereby to release the weight of the bolt from the said yieldable means.

Another object of the present invention is 20 the provision of means whereby the bolt may be withdrawn from its latching position, together with means for retaining the said bolt in its inoperative position against the action of the said yieldable means.

Another object of the present invention is to provide such a bolt embodying generally 25 a base plate, aligned bearing members carried by the base plate and provided with cam faces, and a bolt slidably mounted within 30 the bearings and having means adapted to ride upon the said cam faces as the bolt is moved from its latching position into its inoperative position and vice-versa.

A further object of the present invention 35 is to provide an improved bolt of the above character which will be durable and efficient in use, one that will be simple and easy to manufacture and one which can be placed upon the market at a small cost.

Numerous other objects and advantages of 40 the present invention will become more readily apparent during the course of the following description when taken in connection with the accompanying drawings.

In the drawings forming a part of this application and wherein like characters of reference denote corresponding parts throughout the several views:

Figure 1 is a view of a portion of a garage 50 or like structure showing associated therewith an improved securing bolt constructed in accordance with the present invention.

Figure 2 is a sectional view through a portion of the garage or like structure showing the bolt in a position at right angles to 55 Figure 1.

Figure 3 is a detail view of the bolt looking at the rear thereof.

Figure 4 is a vertical central sectional view through the bolt. 60

Figure 5 is a transverse sectional view taken on line 5—5 of Figure 2. 65

Figure 6 is a transverse sectional view taken on line 6—6 of Figure 4.

Figure 7 is a perspective view of the 65 keeper plate.

Figure 8 is an enlarged detail view showing the formation of one of the notches.

Referring now more particularly to the accompanying drawings, the numeral 10 generally designates the front wall of a garage or other like structure and 11 the door thereof to the frame 12 of which is adapted to be secured the present improved bolt generally indicated by the numeral 13. 70 75

The bolt 13 embodies in its construction a substantially rectangular flat base plate 14 provided at its four corners with apertures 15 through which may be inserted suitable screws or other fastening elements 16 when 80 securing the device to the door frame 12 of the garage or like structure 10.

Carried by the base plate 14 and arranged longitudinally thereof is the somewhat narrower depending guide plate 17 which extends substantially the entire length of the said base plate 14 and is secured thereto intermediate its vertical side edges through the medium of one or more rivets 18, the lower end of the said guide plate 17 being 85 directed at substantially right angles to the body thereof to provide the guide terminal 19. It will be appreciated that means other than rivets may be employed for securing the guide plate 17 to the base plate 14 and therefore, I do not wish to be limited to the particular securing means disclosed. 90 95

Also carried by the base plate 14 are the vertically aligned guide members 20 and 21 within which is slidably mounted the bolt 100 22, said bolt having secured to the lower end thereof the depending operating rod 23 which passes through an aperture in the guide terminal 19 of the plate 17 and has its

lower end angularly directed to provide a hand grip 24 which facilitates the gripping of the rod when it is desired to operate the bolt. An expansible coil spring 25 encircling the rod 23 and having one end secured to the guide terminal 19 of the plate 17 and the other end secured to the bolt 22 serves to normally urge the bolt upwardly into its latching position.

10 It will be readily understood that there are various ways in which the rod 23 may be secured to or within the bolt 22 and I do not, therefore, wish to be limited to any particular manner of securing these elements 15 together. However, I prefer to secure the rod 23 within the bolt 22 by means of soldering, welding or through the process of sweating thereby eliminating the necessity 20 of forming threads on the rod and within the bolt.

The guide members 20 and 21 are of substantially U-shaped formation and have their opposite ends extended through the base plate 14 and flattened as at 26 and 27 whereby to secure the same to the said base plate. 25 It will be seen that the guide members 20 and 21 overlie the guide plate 17 and that the opposite ends of the said guide members pass through the base plate immediately 30 adjacent the vertical edges of the said guide plate.

The bottom edge of the guide member 20 is provided with an upwardly curved cam face 28 terminating in a notch 29, the provision of which results in the formation of the inwardly extending bolt retaining lug 30. The upper edge of the lower guide member 21 is also formed with a cam face 31 but this cam face curves downwardly and 40 in an opposite direction from the cam face 28, said cam face 31 terminating in a notch 32, the provision of which results in the formation of the lower bolt retaining lug 33, the notches 29 and 32 and the bolt retaining lugs 30 and 33 being positioned at 45 opposite sides of the base plate 14 as will be readily understood.

Carried by the bolt 22 approximately intermediate the ends thereof is the laterally extending locking pin 34 adapted to ride upon the cam faces 28 and 31 and to fit within the notches 29 and 32 in the guide members 20 and 21 when the bolt 22 is moved into its locking position or into its inoperative position as will be more clearly herein-after set forth.

In Figure 7 of the drawings has been disclosed the keeper plate employed in association with the present improved bolt, said 60 keeper plate comprising in its construction the base portion 35 formed with the bolt receiving opening 38 and the upstanding forward end 36. The keeper plate is adapted to be counter-sunk into the front wall of the 65 garage or like structure directly above the

door frame 12 as shown in Figures 1 and 2 and the same is secured in position by means of suitable fastening elements adapted to be inserted through the openings 37 in the base portion 35.

70

Before the bolt is attached to the garage or like structure, the top of the door frame 12 thereof is cut out to form a vertical opening or bore 39 and the front wall 10 of the structure directly above the door frame is 75 formed with a recess 40 in alignment with the bore 39. The keeper plate shown in Figure 7 is then secured to the bottom edge of that portion of the front wall 10 of the structure forming the top of the doorway in 80 the manner set forth above so that the opening 38 therein will align with the bore 39 and recess 40.

85

The improved bolt 13 is then associated with the garage or like structure by securing the base plate 14 thereof to the inner side edge of the door frame 12 so that the bolt 22 will be in alignment with and will be permitted to pass upwardly through the bore 39 in the door frame and opening 38 in the 90 keeper plate into the recess 40 in the front wall of the structure.

When it is desired to unfasten the door 11, the operator simply grasps the hand grip 24 on the lower end of the operating rod 23 and turns the same slightly to the left, thereby also turning the bolt 22 whereby to move the locking pin 34 out of the notch 30 in the guide member 20, the locking pin 34 riding on the cam face 28 as the said bolt is being 100 thus turned. When the bolt has been turned sufficiently, to move the locking pin 34 out of the notch 29, it is then pulled downwardly against the action of the spring 25 and as the locking pin 34 engages with the cam face 31 of the guide member 32, the bolt is again turned to the left so that the said latching pin will ride downwardly on the said cam face 31 into the notch 32, said bolt being effectively held in its inoperative position 110 through the medium of the latching pin 34 engaging with the retaining lug 33. Attention is directed to Figure 8 which shows more clearly the exact formation of the notch 32 and it will be seen that the bottom 115 edge of the lug 33 is curved upwardly to form a recess 37 within which is received the latching pin 34. Thus, it will be appreciated that when the latching pin is received within this recess, all danger of the same accidentally slipping out of the notch 32 is obviated.

When it is desired to secure or fasten the door 11, the same is first moved to its closed position after which the operator simply turns the bolt 22 to the right so as to disengage the latching pin 34 from the retaining lug 33 and when the latching pin is so released, the action of the expansion spring 25 will immediately force the bolt upwardly through the bore 39 in the door frame, open- 120

125

130

ing 38 in the keeper plate into the recess 40 in the front wall of the garage or like structure. As the latching pin 34 engages with the cam face 28 of the guide member 20, it will automatically ride upwardly thereon into the notch 29. It will be evident that when the bolt 22 is received within the recess 40 and the latching pin 34 is received within the notch 29 of the guide member 20, the door 11 will be effectively and firmly secured in its closed position.

The bolt retaining lug 30 of the guide member 20 not only serves to release the weight of the bolt 22 from the expansion spring 25 but also serves to prevent the said bolt from moving downwardly out of the recess 40 should the spring 25 be not sufficiently strong to retain the said bolt in its latching position.

It is believed that from the foregoing, the construction and operation of the present invention will be readily understood and it will be appreciated that while there has been disclosed a preferred embodiment of the invention, various changes in the details of construction may be found desirable and the right is hereby reserved to make any such changes as properly fall within the scope of

the appended claim without departing from or sacrificing the spirit of the invention. 30

What is claimed is:

A sliding bolt structure of the character set forth comprising a mounting plate, a pair of longitudinally spaced substantially U-shaped guide members having the legs there- 35 of secured in said plate, said members having the opposed edges each provided with an arcuate cam slot, the open ends of said slots being in alignment and each terminating in a pocket, a bolt member extending through 40 said guide members and a retaining pin carried by said bolt between said guides and designed to selectively engage in said slots to maintain the bolt in projected or retracted position, a guide arm extending longitudi- 45 nally of the face of said plate between the legs of said guides and projecting beyond one end of the plate, and having a guide terminal formed at the outer end thereof, an actuating rod connected with said bolt 50 and extending through said terminal, and a spring member arranged between the terminal and the adjacent end of the bolt to maintain the bolt in set position.

In testimony whereof I affix my signature.

DAVID BOOTH.
